METHOD OF AND APPARATUS FOR MAKING SHOES

Fritz Holland, Long Island City, N. Y., and Isaac F. Damon, Belmont, Mass., assignors to Compo Shoe Machinery Corporation, New York, N. Y., a corporation of Delaware

Application November 1, 1930. Serial No. 492,633

14 Claims. (Cl. 12—38)

This invention relates to the manufacture of shoes, and particularly to methods of and means for adhesively affixing an outer sole to a lasted upper, and has as a general object the provision of methods and means whereby an outer sole 5 may be firmly pressed against the lasted upper, without rolling the edges of the sole.

Another object is to provide means for protecting the outer edges of a sole from being rolled by a pressure pad during the sole affixing operation, while simultaneously allowing pressure to be applied at those points necessary to insure a proper affixation of the sole to the lasted upper.

A further object is to provide an interchangeable guard device of this character which is simple, economical and readily manufactured.

Other objects of the invention will in part be obvious and will in part appear hereinafter.

The invention accordingly comprises the several steps and the relation and order of one or more of such steps with respect to each of the others, and the apparatus embodying features of construction, combination of elements and arrangement of parts which are adapted to effect such steps, all as exemplified in the following detailed disclosure, and the scope of the application of which will be indicated in the claims.

For a fuller understanding of the nature and objects of the invention references should be had to the following detailed description taken in connection with the accompanying drawing, in which:

Fig. 1 is a transverse sectional view of a sole affixing apparatus embodying the invention;

Fig. 2 is a bottom view of the interchangeable guard device; and

Fig. 3 is a side elevation of the device shown in Fig. 2.

In manufacturing shoes wherein the outer sole 40 is attached to the upper by means of an adhesive, with or without other attaching means, it is customary to first last the upper and lining to an inner sole, and then to apply the outer sole to such lasted upper. In effecting this last operation, 45 according to one method, an adhesive coating is interposed between the upper and outer sole, and these parts are then placed in their proper relation in a press, and kept therein until the adhesive sets. The type of press usually employed for this purpose includes a flexible diaphragm, or 50 fluid container, which is adapted forcibly to press or "balloon" against the outer surface of the outer sole. This diaphragm extends over the entire sole surface, so as to assure adhesion between the marginal portions of the upper and sole,

and also extends an appreciable distance beyond the periphery of the outer sole, so that when fluid pressure is applied beneath the diaphragm the latter not only presses against the entire outer surface of the sole, but also has a tendency to 60 bend up or roll the marginal portion of the sole, particularly the extreme outer portions thereof, which are not subjected to opposing resisting pressure by the last. This is especially true in those shoe styles wherein a wide edge sole is used. 65

Referring more particularly to the drawing, and especially to Fig. 1, 10 denotes the base of a conventional type of sole press, which press also includes a flexible upper pressure applying diaphragm 11, and a means 12 for holding a lasted 70 upper 13 and an outer sole 14 in pressing relationship with diaphragm 11.

In ordinary practice prior to the present invention, when affixing the outer sole to the upper, an adhesive cement was applied to the outer sole 75 and the lasted upper, and the shoe was placed in the press with a pressure applying diaphragm such as 11 directly engaging the outer sole. Pressure applied through such a diaphragm, or its equivalent, directly to the outer sole was thus 80 exerted equally against all points on the sole surface, and acted to roll up or curl the marginal portions of the sole in the undesirable manner hereinbefore mentioned.

To avoid this a novel pressure applying guard 85 means generally designated at 15 is interposed between the outer sole 14 and diaphragm 11 during the sole affixing process. This means comprises a generally U-shaped rigid member or strip 16, which is preferably made of thin but substantially inflexible sheet metal. An upstanding marginal flange 17, extends around the outer edge of member 16, such flange being adapted to snugly, but not bindingly, fit about the periphery of the forepart of a sole 14. Bridging the space between 95 the arms of member 16, and on the lower sides thereof extending oppositely with respect to flange 17 is a pressure transmitting element or block 18. Such element is formed of a slightly flexible but fairly stiff material, such as sole 100 leather, and may be fastened to member 16 by any suitable means such as rivets or clasps 19. A member having a rigid outer margin, but a somewhat yielding inner or central portion is thus formed.

Element 18 conforms generally in outline with the outer edge of member 16, but is preferably of smaller size than such member, leaving a margin 20 between the outer edge of element 18 and flange 17 which marks the outer edge of mem- 110

ber 16. That is, element 18 is adapted to transmit pressure directly to the central and the adhesively coated portions toward the margins of sole 6 without directly bearing on the outward 5 marginal portions thereof, as shown in Fig. 1. Element 18 in the embodiment shown, is also extended rearwardly somewhat beyond member 16, and at the rearward or instep portion thereof is gently tapered as at 21, so that there will be 10 no abrupt change of contour at the juncture between element 18 and sole 14 and so that it is more flexible at this point.

Preferably a sheet of non-abrasive material 22, such as soft leather, is fitted across the upper 15 side of member 15 between flanges 17 to avoid scarring the impressed sole 14.

In using the novel device above described, a 20 previously cemented lasted upper and sole are juxtaposed in their proper relationship. Member 15 is then positioned beneath the sole with flange 17 embracing the periphery thereof. This assembly is then placed in the press with diaphragm 11 engaging member 15 and means 12 holding the lasted upper against upward 25 placement. The pressure is then increased to the desired extent, usually by inflating the pad beneath the shoe. Diaphragm 11 will then press upwardly toward the shoe with a uniform pressure at all points on such diaphragm, and its 30 flexibility will cause it to adopt a configuration substantially as shown in Fig. 1. Force is transmitted directly through the slightly flexible element 18 to the central part of sole 14, thus holding the latter in a flat non-bulging position and 35 causing a firm pressing engagement between the sole and upper throughout such area. Since element 15 is of such extent that it approximately reaches to the contact line between the upper and the sole, full adhesion is assured, marginal 40 pressure being transmitted through element 18 and member 16. Slight pressure may also be applied against the sole through the marginal portion 20 of member 18, as a result of the direct 45 engagement of diaphragm 11 with the outer part of such margin 20, but any tendency to curl or roll the marginal portion of the sole is resisted by the inherent rigidity of member 16.

The flexibility of element 18 is such that the 50 device is sufficiently responsive to deforming forces to adapt itself to the desired configuration. Thus, it may be bent fairly readily to conform to the contour of the usual shoe sole, so as to press closely against the flat central portion 55 thereof, and yet follow receding portions such as the shank. Any pronounced rolling of the sole edges is effectively precluded however, by applying pressing forces thereto in the above described manner.

It will be seen that the flanged guard 15, can 60 be made in various sizes, and that the guards are in the form of portable units which may be interchangeably used with a number of different presses and shoes.

Since certain changes in carrying out the above 65 process and in the constructions set forth, which embody the invention may be made without departing from its scope, it is intended that all matter contained in the above description or shown in the accompanying drawing shall be 70 interpreted as illustrative and not in a limiting sense.

It is also to be understood that the following 75 claims are intended to cover all of the generic and specific features of the invention herein described, and all statements of the scope of the in-

vention which, as a matter of language, might be said to fall therebetween.

Having described our invention, what we claim as new and desire to secure by Letters Patent, is:

1. A process of making shoes which comprises, in combination, placing a sole against an upper with adhesive therebetween; placing a flexure resisting protecting means about a marginal portion only of said sole adjacent the lower side thereof; positioning a flexure-permitting pressure-transmitting element adjacent said sole and beneath said flexure resisting protecting means and applying pressure to said element during the setting of the adhesive. 80

2. A process of making shoes which comprises, in combination; placing a sole against an upper with adhesive therebetween; placing a flexure resisting protecting means about a marginal portion only of said sole; positioning a flexure-permitting pressure-transmitting element adjacent said sole with the edges of said element approaching but not reaching the edges of said sole, and applying pressure to said element during the setting of the adhesive. 85

3. A process of making shoes which comprises, in combination; placing a sole against an upper with adhesive therebetween; placing a flexure resisting protecting means about a marginal portion only of said sole; placing a flexure-permitting pressure-transmitting element adjacent said sole with the edges of said element approaching but not reaching the edges of said sole; applying a given pressure per unit of area to said element during the setting of the adhesive; and 100 simultaneously applying a reduced pressure per unit of area to said means.

4. A shoe protector insertable between a shoe sole and a pressure pad during a sole pressing operation, comprising a substantially U-shaped outer sole protecting member in combination with a pressure transmitting element disposed across and in engagement with the arms of said member. 115

5. A shoe protector insertable between a shoe sole and a pressure pad during a sole pressing operation, comprising an outer sole protecting strip substantially conforming in shape and extent with the outline of the forepart of a shoe sole and having spaced portions enclosing a central aperture, in combination with a pressure transmitting element disposed across said aperture and in engagement with spaced portions of said strip. 125

6. A device of the class described, comprising a substantially U-shaped protecting member in combination with a pressure transmitting element disposed across the arms of said member, said element being of decreasing thickness along the edge thereof which extends across the open 135 end of said U-shaped member.

7. A device of the class described, comprising a flexure resisting protecting means substantially conforming in shape with the outline of the forepart of a shoe sole, said means being provided on one side thereof with an upstanding marginal flange, and a pressure transmitting means disposed adjacent said protecting means and on the opposite side thereof from said flange. 140

8. A device of the class described, comprising a member substantially conforming in shape with the outline of the forepart of a shoe sole, guide means on said member adapted to snugly position it on such sole, and a pressure transmitting element positioned on the opposite side of said 145 150

member from said guide means, said element substantially corresponding in shape with but being of less area than such sole.

9. An interchangeable, portable guard unit, comprising a flexure resisting protecting strip adapted to be placed along the marginal portion only of a shoe sole, in combination with a flexible pressure transmitting element permanently secured to said strip.

10. A device of the class described, comprising a flexure resisting protecting strip substantially conforming in shape and extent with the marginal portion only of the forepart of a shoe sole, and a pressure transmitting element adjacent said protecting strip, the side edges of said element being substantially parallel to the side edges of said strip and spaced inwardly therefrom.

11. A device of the class described, comprising a flexure resisting protecting strip substantially conforming in shape with the outline of the forepart of a shoe sole, a flexible pressure transmitting element disposed on one side of said strip, and a non-abrading cover on the other side of said strip.

12. In a shoe pressing device, in combination, means for supporting and protecting the marginal portion of a shoe sole against rolling, means for transmitting pressure to such sole, and a single pressure applying pad acting on the two first-named means.

13. In a shoe pressing device, in combination, means for protecting the marginal portion of a shoe sole against rolling, means for transmitting pressure to such sole, comprising a block substantially conforming in shape with the forepart of such sole but having the bounding edges thereof spaced inwardly from the edges of the same, and a single pressure applying means acting against said block and protecting means.

14. An interchangeable, portable guard unit, comprising a flexure resisting protecting strip adapted to underlie the marginal portion only of a shoe sole, and to be supported upon a flexible pad, in combination with a flexible pressure transmitting element.
